CLAIM

The ornamental design for a packaging container, as shown and described.

DESCRIPTION

FIG. 1 is front, right perspective view of a packaging container showing our new design.

FIG. 2 is left side elevational view thereof.

FIG. 3 is front elevational view thereof.

FIG. 4 is a right side elevational view thereof.

FIG. 5 is a rear elevational view thereof.

FIG. 6 is a top plan view thereof; and,

FIG. 7 is a bottom plan view thereof.

The broken lines shown in the drawings depict portions of the packaging container that form no part of the claimed design.
